Primary Examiner—Cathron Brooks*(74) Attorney, Agent, or Firm*—Brinks Hofer Gilson & LioneCLAIM

The ornamental design for a television stand, as shown and described.

DESCRIPTION

FIG. 1 is a front perspective view of a television stand of the present invention;

FIG. 2 is a rear perspective view thereof;

FIG. 3 is a top view thereof;

FIG. 4 is a front view thereof;

FIG. 5 is a rear view thereof;

FIG. 6 is a first side view thereof; and,

FIG. 7 is a second side view thereof.

The ornamental design which is claimed is shown in solid lines in the drawings. Any broken lines in the drawings are for illustrative purposes only and form no part of the claimed design.
